QUICK START AND STOP MECHANISM FOR
PHONOGRAPH TURNTABLESLincoln Thompson, Stamford, Conn., assignor to
The SoundScriber Corporation, Stamford,
Conn., a corporation of Connecticut

Application November 26, 1938, Serial No. 242,598

2 Claims. (CL 274—9)

This invention relates to phonographs having records of the disc type, and more particularly to a mechanism for quickly starting and stopping the rotation of the record in order to facilitate the transcription thereof by a typist.

One object of this invention is to provide a start and stop mechanism of the above nature which will be provided with a light weight, low inertia turntable having a friction slip clutch connection with a continuously running motor.

A further object is to provide a start and stop mechanism of the above nature employing a pivoted electromagnetic brake member operated by a foot-controlled switch and adapted to engage the rim of the turntable whenever it is desired to stop the record.

A still further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may be embodied in practice.

The single figure on the drawing represents a section taken through the turntable, the disc record, and the magnetic brake, and shows diagrammatically the remainder of the apparatus and electrical circuits.

In receiving news messages over the telephone, by wireless, and by dictation, the communications are often recorded on phonograph disc records, which records are then replayed to reproduce the messages on a phonograph, so that a typist may typewrite them for use in the editorial department of a newspaper. The present invention is of great importance in facilitating the quick starting and stopping of the turntable which supports the record without stopping the motor.

Referring now to the drawing, the numeral 10 indicates a rotary turntable of thin light weight metal, such as aluminum. The turntable 10 preferably has a downturned flange 10a on its periphery and a relatively thick block 10b at its center. The central block 10b is provided with an aperture 10c which is adapted to surround a vertical pin 11 for centering a disc record 12 which is adapted to be supported upon the turntable 10. The centering pin 11 is preferably formed integral with a driving plate 13, which is connected with the block 10b by means of a slip friction clutch 14. The driving plate

13 is supported by a depending shaft 15 which is driven continuously by an electric motor 16 located below the same.

In order to reproduce the messages recorded in the grooves of the disc record 12, provision is made of an electrical pick-up member 17 having a needle 18 adapted to travel within the grooves of said record. The pick-up 17 is connected by a pair of conductors 19 and 20 to an audion amplifier 21 receiving power through conductors 22 and 23, a two-prong plug 24 and a socket 25, which in turn is connected to a pair of A. C. line conductors 26 and 27. The output of the amplifier 21 passes through a pair of conductors 28 and 29 to a loud speaker 30, or if desired, to a pair of head phones or a telephone receiver, not shown.

In order to energize the electromagnetic brake for stopping the turntable whenever desired, a pair of conductors 31 and 32 lead from the conductors 22 and 23, respectively, to a rectifier 33 which converts the alternating current from the line into direct current, but it will be understood that if desired this rectifier may be omitted within the spirit and scope of the invention.

A conductor 34 leads from one output terminal of the rectifier to a foot-operated switch comprising a movable contact member 35 having an upwardly extending button 36 and a pair of stationary contacts 37 and 38 adapted to be bridged by the movable contact 35 whenever the button 36 is depressed by the foot of the operator. A coiled spring 39 is located under the movable contact to automatically raise it to the normal open circuit position shown in the drawing. A conductor 40 leads from the contact 38 to an annular electromagnetic coil 41, which coil is also connected to the rectifier by a conductor 42. Loosely fitted within the interior of the coil 41 is the central member of a U-shaped soft iron core 43, the horizontal lower leg 44 of which is provided with an upstanding iron brake rod 45 pivoted at 46 to the end of said horizontal leg 44. At the upper end of the brake rod 45 provision is made of a cylindrical brake shoe 47, preferably constructed of rubber and which is located in alignment with the flange 10a of the turntable 10. The brake rod 45 is normally held in the inoperative position shown in the drawing by means of a coiled spring 48 secured to a fixed bracket 49.

Operation

In operation, when it is desired to stop the rotation of the turntable 10, the operator will depress the button 36 of the foot-switch with

his foot, closing the circuit through the electro-magnetic coil 41,—thus energizing the magnetic core, the upper leg of which will attract the iron brake rod and cause the brake shoe 47 to engage the depending flange 10a of the turntable, and stop the rotation thereof instantly. The motor, however, will continue to rotate,—this being made possible by the friction slipping connection mentioned above.

It will be understood that the friction between the driving plate 13 and the clutch 14 should be made small enough so that when the turntable is stopped by the brake shoe 47, the motor will not be slowed down, but will continue to rotate at full speed. At the same time the friction should be large enough to insure the instant starting of the turntable at full speed when the brake shoe is disengaged from the turntable without being retarded by the work required to move the needle in the grooves of the disc record.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a phonograph, a low inertia turntable having a depending flange around its periphery, a brake shoe for engaging said flange whenever it is desired to stop the rotation of the turntable, a spring-retracted pivotally-mounted iron rod for supporting said brake shoe, and a foot-controlled electromagnet for selectively attracting said iron rod for causing said brake shoe to engage said flange and stop said turntable, continuously rotating driving means, and a slip-friction clutch for connecting said driving means with said turntable, whereby the stopping of said turntable will not stop the rotation of said driving means.
2. In a phonograph, a low inertia turntable, a brake shoe for engaging said turntable whenever it is desired to stop the rotation thereof, a spring-retracted iron rod for supporting said brake shoe, a manually-controlled electromagnet for selectively attracting said iron rod for causing said brake shoe to engage and stop said turntable, continuously rotating driving means, and a slip-friction clutch for connecting said driving means with said turntable, whereby the stopping of said turntable will not materially slow down the rotation of said driving means.

LINCOLN THOMPSON.
